FLAME DETECTING APPARATUS WITH FLAME SIMULATION TEST
 Fred T. Deziel, Bloomington, Minn., assignor to Honeywell Inc., a corporation of Delaware
 Filed Sept. 7, 1961, Ser. No. 136,589
 7 Claims. (Cl. 340—214)

The present invention is concerned with an improved condition detecting apparatus in which the apparatus is constructed and arranged to provide a check of the system at periodic intervals and to energize a fault indicating means should the system not respond properly to this preiodic checking.

In the preferred embodiment of my invention I show the condition detecting apparatus as incorporating fire detecting means which is periodically subjected to a fire simulating source. Prior art devices are known wherein a condition sensor is checked by subjecting the sensor to the simulated condition to be detected. However, my invention utilizes an improved combination of elements to provide a more foolproof means for checking the operation of the fire sensing means.

Specifically, my apparatus utilizes a sensor which scans or views the area under supervision in individual discrete segments. At one position, or one such discrete segment, a fire simulating element is viewed. Thus, in the absence of fire, the fire sensing means provides an output signal for each time that it passes this particular segment of the area being supervised. Cycling switch means, controlled in a predetermined relation with the scanning by the flame sensing means, is provided to energize a fire alarm means during all portions of the viewing by the fire sensor with the exception of that time during which the particular area is being viewed, to thus sound a fire alarm should a fire be detected in these segments. A fault alarm means is also provided and this means is arranged to be energized in the event that the fire sensor does not respond to the presence of the fire simulating means at that particular interval in the viewing by the fire sensing means. Thus, I provide greater reliability since not only is the operativeness of the fire sensing means periodically checked, but this operativeness is specifically related to a predetermined sequence of viewing by the fire sensing means.

In the preferred embodiment of my invention I provide an electrical motor to control the rotation or scanning of a fire sensing means and, as a further feature of my invention, I provide means to sense continuous operation of this motor and to energize a fault alarm in the event that this motor stops rotating.

My invention will be apparent to those skilled in the art upon reference to the following specification, claims, and drawings, of which:

FIGURE 1 is a schematic representation of an area to be supervised in which an ultraviolet responsive fire sensor is located, showing the relationship of an ultraviolet source to simulate fire.

FIGURE 2 is a schematic showing of my invention, and FIGURE 3 is a graph showing fire sensor output versus degrees of rotation of the fire sensor, the fire sensor output of FIGURE 3 being for the condition wherein no fire is actually present within the area to be supervised.

Referring to FIGURE 1, reference numeral 10 identifies generally an area to be supervised, this being for example a warehouse which is left unattended for long periods of time and in which the presence of fire would go undetected for a considerable length of time. In actual practice, my invention is not limited to a specific application but rather to a generic consideration of an area which is to be supervised. Located within this area in an ultraviolet responsive fire sensor indicated generally by means of reference

2

numeral 11. Here again, the specific type fire sensor is not considered to be a limitation of my invention. The construction of means 11 includes a rotating platform 12 (see FIGURE 2) mounted on a stationery base or support member 13 and having a reflector 14 to control the viewing angle or scan of an ultraviolet responsive photocell 15.

In FIGURE 1 photocell 15 is viewing a portion of the complete 360 degree circle of rotation traversed by the photocell 15, as it views the area to be supervised in discrete intervals, and is centered at the 90° point.

In accordance with the teachings of the present invention, a fire simulating means is provided at a particular one of the intervals successively viewed by the fire sensor. In FIGURE 1 this means is indicated by reference numeral 16, referring to the ultraviolet source to simulate fire. In actual practice this may be a continuously energized source of ultraviolet energy which is effective to simulate the presence of fire at the 270 degree portion of the successive scanning by the fire sensor.

Referring now to FIGURE 3, this figure shows the output of the photocell 15 plotted as a function of the particular portion of the area to be supervised of FIGURE 1 which is being viewed. Thus, at the 270 degree interval point, photocell 15 is viewing ultraviolet source 16 and thus a simulated fire signal is present. For all other portions of the 360 degrees of rotation of photocell 15, no output is present. If a fire should occur at a particular interval, an output will be effective, at this interval, to energize an alarm means, as will be described.

Referring now to FIGURE 2, photocell 15 is connected to the input of an amplifier 20, whose output includes a relay 21 having a normally closed switch 22 and a normally open switch 23. Relay 21, which can be defined as a fire relay, is shown in its de-energized condition wherein switch 22 is closed and switch 23 is open. As is conventional, energization of relay 21 causes switches 22 and 23 to assume the opposite condition of operation wherein switch 22 is open and switch 23 is closed. Amplifier 20 is connected to a source of supply voltage, not shown, by means of conductors 24 and 25.

Reference numeral 26 designates generally a motor means including a motor 27 continuously energized from a source of alternating voltage, not shown, connected to power line conductors 30 and 31. Motor 27 is connected through mechanical linkages designated by means of reference numerals 32 and 33 to control the rotating platform 12 on which photocell 15 is mounted and to control cycling switch means designated generally by means of reference numeral 34.

Cycling switch means 34 includes three cams 35, 36 and 37 which continuously rotate with rotation of motor 27, the direction of rotation being indicated by means of arrows. Cam 35 is operatively associated with a switch 40 and the means 35-40 is constructed and arranged to maintain switch 40 in a closed condition for all portions of the cycle of rotation of photocell 15 except during that portion in which the photocell views the ultraviolet source 16 (the 270 degree interval of FIGURE 1). Cam 36 is associated with a switch 41 and the means 36-41 is constructed and arranged to maintain switch 41 in an open condition for all portions of the sweep or cycle of operation of photocell 15 except for that portion in which photocell 15 views the ultraviolet source 16. Cam 37 is associated with switches 42 and 43, these switches being alternately closed and opened at a regular interval, for example once for every 90 degrees rotation of photocell 15.

The above mentioned switch 41 is connected in circuit with a trouble alarm relay 44 having a pair of normally open switches 45 and 46. Relay 44 is shown in the de-energized condition wherein switches 45 and 46

are open. Upon energization of relay 44, these switches close.

Switch 40 is connected in circuit with a fire alarm relay 50 including normally open switches 51 and 52. Here again, relay 50 is shown in the de-energized condition. Upon energization of relay 50 switches 51 and 52 close.

Switches 42 and 43 are associated with a checking relay 53 having a switch 54. Relay 53 is shown in the energized condition, this being the normal condition indicative of continuous operation of motor 57. In order to obtain continuous energization of relay 53 in response to continuous rotation of motor 57, a bridge rectifier 55 is connected to power line conductors 30 and 31 and the output of this bridge rectifier is connected through switch 42 to charge a capacitor 56. However, as the motor 27 continues to rotate, the charged capacitor 56 is now connected through switch 43 to charge a further capacitor 57 to thus maintain relay 53 continuously energized so long as the switch means 42-43 continues to cycle, this being indicative of continuous rotation of motor 27.

Considering now the operation of my improved condition detecting apparatus in greater detail, the apparatus of FIGURE 2 shows the fire sensing photocell 15 as viewing the 90 degree interval of the area to be supervised of FIGURE 1. Furthermore, no flame is present at this portion of the area to be supervised. The photocell 15 continues to be driven in a counterclockwise direction as shown by the arrow adjacent platform 12 of FIGURE 2, and sweeps the area to be supervised. Since no fire is present, fire relay 21 is maintained de-energized. When photocell 15 views the 270 degree portion of the area to be supervised, the ultraviolet source 16 is detected and fire relay 21 is energized. However, it will be remembered that at this time switch 40 has opened and switch 41 has closed due to action of cams 35 and 36 respectively. Thus, as will be apparent, the fire alarm relay 50 is prevented from being energized and the trouble alarm relay 44 is likewise prevented from being energized.

For purposes of a more complete description of the operation of my invention assume for the moment that a component failure has occurred within amplifier 20 such that the photocell 15 is incapable of sensing the actual presence of fire. If this is true, photocell 15 likewise will not sense the presence of ultraviolet source 16 and thus fire relay 21 is maintained in a de-energized condition at the 270 degree interval of the area to be supervised. As has been pointed out above, switch 40 is open and switch 41 is closed at this portion in the sweep of the area to be supervised by photocell 15. With the assumed component failure, an energizing circuit for trouble alarm relay 44 can now be traced from power line conductor 30 through switch 41, switch 22, and trouble alarm relay 44 back to power line conductor 31. Thus, switches 45 and 46 are closed. The closing of switch 45 completes a holding circuit directly connecting relay 44 across power line conductors 30 and 31. The closing of switch 46 completes a circuit which has been labeled "to trouble alarm" and thus a trouble alarm of one form or another is energized to indicate that the apparatus has become inoperative.

Assume now that a fire occurs somewhere within the area to be supervised other than at the 270 degree portion of the area. This source of ultraviolet energy will be sensed by photocell 15 to energize fire relay 21. Switch 40 is now closed and switch 41 is open and thus an energizing circuit can be traced for fire alarm relay 50 from power line conductor 30 through switch 40, switch 23, and fire alarm relay 50 to power line conductor 31. Energization of fire alarm relay 50 causes switches 51 and 52 to move to a closed condition. Switch 51 in its closed condition completes a holding circuit to maintain fire alarm relay 50 connected across

power line conductors 30 and 31. The closing of switch 52 completes a circuit labeled "to fire alarm" to thus sound or energize a fire alarm in one form or another to indicate that a fire has occurred within the area to be supervised.

Thus, as above described, it can be seen that I have provided an improved condition detecting apparatus wherein the condition is simulated at the particular interval within the area to be supervised and in which, through the medium of cycling switch means, the ability of the condition sensor 15 to sense the presence of a simulated condition is checked during each cycle of operation of the apparatus. Since proper checking of my apparatus depends upon continued rotation of motor 27, I provide as a further feature of my invention a means to sense a failure of motor 27 to continue to rotate. As has been pointed out, continuous rotation of motor 27 is necessary to cause switches 42 and 43 to cycle, switches 42 and 43 alternately being opened and closed to charge capacitor 56 and then to transfer this charge to capacitor 57. Should switches 42 and 43 fail in either the open or closed position, relay 53 is de-energized to close switch 54. This switch is in parallel with switch 46 of the trouble alarm relay 44 and in a like manner is effective to energize a trouble alarm to indicate that the apparatus has developed a fault. Thus, I provide the optimum in safety in a condition detecting apparatus, not only subjecting the apparatus to a periodic condition to be simulated, but also requiring that this condition to be simulated occur at a particular interval in the cycle of operation of my apparatus, and also requiring continuous operation of the cycling means.

Other modifications of this invention will be apparent to those skilled in the art and it is therefore intended that the scope of the present invention be limited solely to the scope of the appended claims.

I claim as my invention:

1. Condition detecting apparatus for use in supervising an area comprising; condition sensing means sensitive to the presence of a given condition, rotatable blocking means to restrict the field of view of said condition sensing means, supervising means including said blocking means and said condition sensing means adapted to continuously sweep the area to be supervised in successive discrete segments, condition simulating means adapted to be positioned at a given location within the area to thereby simulate the given condition at the given location, and output means connected to said supervising means, said output means including an alarm output effective upon said condition sensing means sensing the presence of the given condition at any position in said area other than said given location, said output means including a fault output effective upon failure of said condition sensing means to sense the presence of said condition simulating means at said given location.

2. Condition detecting apparatus for use in supervising a given area to provide a primary output upon the occurrence of a given condition within the area, comprising; condition sensing means, rotatable reflecting means, supervising means including said reflecting means and said condition sensing means adapted to sweep the area to be supervised to thus cause said condition sensing means to successively view small portions of the area, condition simulating means adapted to be located at a predetermined position within the area, output means connected to said supervising means to provide a primary output upon said condition sensing means sensing the presence of the given condition at any position in said area other than at said predetermined position, and to provide a fault output upon failure of said condition sensing means to sense the presence of said condition simulating means at said predetermined position, and fault indicating means connected to said supervising means to detect and announce a failure in the operation thereof.

3. Fire detecting apparatus for use in supervising an

area having a first portion and a second portion to provide an alarm output in the case of a fire within the area, comprising; fire sensing means, fire simulating means adapted to be positioned in the first portion of the area, and supervisory means including movable reflecting means and said fire sensing means adapted to cause said fire sensing means to sweep the area to successively view the first and second portions of the area and including further means to condition an alarm output to be effective upon said fire sensing means sensing the presence of fire in the second portion of the area and to condition a fault output to be effective upon said fire sensing means failing to sense the presence of said fire simulating means in the first portion of the area.

4. Fire detecting apparatus for use in monitoring the presence or absence of fire in an area to be supervised, comprising; fire sensing means, support means for said fire sensing means, a motor, means connecting said motor to said support means to thereby rotate said support means and cause said first sensing means to sweep the area to be supervised and to view the area in successive intervals, fire simulating means adapted to be positioned at a particular interval in the area to be supervised, a flame relay, means connecting said flame relay to be controlled by said fire sensing means to actuate the same upon said fire sensing means sensing the presence of fire or the simulated presence of fire, a fire alarm relay, cyclic switch means, means connecting said cyclic switch means to be controlled by said motor, energizing circuit means for said fire alarm relay controlled by said cyclic switch means and by said fire relay to energize said fire alarm relay upon said fire sensing means sensing the presence of fire at any interval in said area other than said particular interval, a fault alarm relay, and circuit means controlled by said cyclic switch means and said fire relay to energize said fault alarm relay upon failure of said fire sensing means to detect said fire simulating means at said particular time interval.

5. Fire detecting apparatus for use in monitoring the presence of fire in an area to be supervised, comprising; fire sensing means, motor means, means connecting said motor means to said fire sensing means to cause said fire sensing means to sweep the area to be supervised and to thus view this area in successive intervals, fire simulating means adapted to be positioned at a particular interval in the area to be supervised, a fire relay, means connecting said fire relay to be controlled by said fire sensing means to be energized thereby, cyclic switch means, means connecting said cyclic switch means to be controlled by said motor means, said cyclic switch means including a normally closed first switch, said motor being adapted to open said first switch during the period in which said fire sensing means views said particular interval of the area to be supervised, said cyclic switch means including a second switch which is closed during said particular interval, a fire alarm relay, circuit means controlled by the first switch of said cyclic switch means and by said fire relay to energize said fire alarm relay upon said fire sensing means sensing the presence of fire during that period in which said first switch is closed, a fault alarm relay, circuit means controlled by said second switch and by said fire relay to energize said fault alarm relay upon failure of said fire sensing means to sense the fire simulating means during that interval in which said fire sensing means is viewing said fire simulating means, fault alarm means, and further switch means connected to said motor

means, said further switch means being responsive to continuous operation of said motor means and effective to energize said fault alarm upon failure of said motor means to be continuously operative.

- 5 6. Fire detecting apparatus for use in supervising an area to protect against the occurrence of a fire, comprising; fire sensing means, a fire relay having a first switch closed in the presence of fire and a second switch opened in the presence of fire, means connecting said fire relay to said fire sensing means to be controlled thereby, motor means, means including blocking means, said motor means and said fire sensing means to cause said fire sensing means to view successive portions of the area to be supervised, fire simulating means adapted to be located in 10 a selected portion of the area, cycling switch means including first and second switches which are arranged to be alternately closed, means connecting said motor means to said cycling switch means to cause said first switch of said cycling switch means to be open and said second switch to be closed during the period in which said fire sensing means views said fire simulating means, an alarm relay having a pair of switches which are closed upon energization thereof, energizing circuit means for said alarm relay including said first cycling switch means 15 20 switch and said first fire relay switch, holding circuit means for said alarm relay including one of said pair of alarm relay switches, an alarm circuit connecting in series the other of said pair of alarm relay switches, a fault relay having a pair of switches which are closed upon energization thereof, energizing circuit means for said fault relay including said second cycling switch means switch and said second fire relay switch, holding circuit means for said fault relay including the one of said pair of fault relay switches, and a fault circuit connecting in 25 30 35 series the other of said pair of fault relay switches.
7. Fire detecting apparatus, comprising; fire sensing means located in an area to be supervised, said area having a first sector and a second sector, motor means, support means for said fire sensing means including rotatable 40 blocking means to restrict the field of view of said fire sensing means to a portion of said area, means connecting said motor means to said support means to thereby rotate said blocking means and cause said fire sensing means to alternately view the first and second sectors of said area, fire simulating means located in said first sector, switch means, means connecting said motor means to said switch means to continuously operate the same in a cyclic manner, principal output means, means including said switch means connecting said principal output means to be controlled by said fire sensing means during the period in 45 50 55 which said fire sensing means views said second sector, secondary output mean, and means including said switch mean connecting said secondary output means to be controlled by said fire sensing means during the period in which said fire sensing means views said first sector.
